DESIGN FOR A SET OF GAME PIECES

Bert J. Bratt, Chicago, Ill.

Application November 19, 1938, Serial No. 81,232

Term of patent 14 years

To all whom it may concern:

Be it known that I, Bert J. Bratt, a citizen of the United States, residing at Chicago, in the county of Cook and State of Illinois, have invented a new, original, and ornamental Design for Set of Game Pieces, of which the following is a specification, reference being had to the accompanying drawing, forming a part thereof.

Figures 1, 2, 3, 4, 5, 6, 7, 8, 9, 10, 11, 12, 13, 14 and 15 are side elevational views of the game pieces, showing my new design; and

Figures 1^a, 2^a, 3^a, 4^a, 5^a, 6^a, 7^a, 8^a, 9^a, 10^a, 11^a, 12^a, 13^a, 14^a and 15^a, are plan views respectively of the game pieces shown in Figures 1, 2, 3, 4, 5, 6, 7, 8, 9, 10, 11, 12, 13, 14 and 15.

I claim:

The ornamental design for a set of game pieces, substantially as shown.

BERT J. BRATT.
